(57) **CLAIM**

The ornamental design for an energy monitoring device, as shown and described.

DESCRIPTION

FIG. 1 is a top perspective view of a first embodiment of an energy monitoring device;

FIG. 2 is a front side view thereof;

FIG. 3 is a top side view thereof;

FIG. 4 is a left view thereof;

FIG. 5 is a right view thereof;

FIG. 6 is a bottom view thereof;

FIG. 7 is a back view thereof;

FIG. 8 is a top perspective view of a second embodiment of an energy monitoring device;

FIG. 9 is a front side view thereof;

FIG. 10 is a top view thereof;

FIG. 11 is a left view thereof;

FIG. 12 is a right view thereof;

FIG. 13 is a bottom view thereof; and,

FIG. 14 is a back view thereof.

The current and voltage conductors have been shown in various positions throughout the views to illustrate the flexible nature thereof.
